[57] **CLAIM**

The ornamental design for a wheel frame for in-line roller skates, as shown and described.

DESCRIPTION

FIG. 1 is right side view of a wheel frame for in-line roller skates illustrating my new design, the left view being identical in appearance;

FIG. 2 is a top plan view thereof;

FIG. 3 is a bottom plan view thereof; and,

FIG. 4 is a front elevation view thereof, the rear view being identical in appearance.

The broken lines showing a boot are for illustrative purposes only and forms no part of the claimed design.

FIG. 1.

FIG. 2.

FIG. 3.

FIG. 4.
